UNITED STATES PATENT OFFICE.

WILLIAM SEVERNS, OF CHICAGO, ILLINOIS.

MOP.

Application filed August 17, 1921. Serial No. 493,015.

To all whom it may concern:

Be it known that I, WILLIAM SEVERNS, a citizen of the United States, and a resident of the city of Chicago, in the county of Cook and State of Illinois, have invented certain new and useful Improvements in Mops; and I do hereby declare that the following is a full, clear, and exact description of the same, reference being had to the accompanying drawings, and to the numerals of reference marked thereon, which form a part of this specification.

This invention relates to improvements in mops, especially those mops adapted for the polishing of floors and the like, and has for one of its objects the provision of such a mop having a head from which the mop material proper may be removed whenever desired.

In the use of such polishing and dusting mops it has been found that the mop material of yarn, cords or fibre will wear out much more quickly than the frame or metal plates composing the head of the mop and the handle fastened thereto, and it has been a much desired object to provide a mop of this sort wherein the mop material may be readily replaced when the same has become worn through use.

It is therefore an important object of this invention to provide a mop or the like wherein the mop material or fabricated cord is readily removable for cleansing and replaceable with a minimum of labor and expenditure of time.

A further object of the invention is the provision of a mop having a removable body portion which can be conveniently and readily mounted in operative position and which can be so mounted that it will be positively secured upon the frame or head with no liability of becoming loose or falling off in use, no matter how severe.

Another object of this invention is the provision of a mop head so shaped that a removable mop body will automatically conform or adapt itself to the head when attached thereto.

Still another important object of this invention is the provision of a mop body provided for attachment to a mop head or frame provided with means whereby it can be readily attached and detached from a mop holding frame.

It is an important object of this invention to provide an adjustable fastening element

upon a mop head whereby a mop body may be attached thereto and its relation thereto adjusted to accommodate the preference of the user thereof and also to make allowances for any variations such as stretching which may occur in a mop body which has been used for some time.

This application is a continuance of my copending application Serial No. 451,008 for "mop," filed March 9, 1921.

Other and further important objects of this invention will be apparent from the disclosures in the accompanying drawings and following specification.

The invention (in a preferred form) is illustrated in the drawings and hereinafter more fully described.

On the drawings:

Figure 1 is a top plan view of the improved form of mop as contemplated by this invention.

Figure 2 is a sectional view taken on the line 2—2 of Figure 1 looking in the direction indicated by the arrows.

Figure 3 is a modification of the mop head fastening means shown in Figure 2.

Figure 4 is a section taken approximately on the line 4—4 of Figure 2 looking in the direction indicated.

Figure 5 is a top plan view of the mop holding frame or plate.

Figure 6 is a similar view showing a slight modification.

Figure 7 is a top plan view of a mop holding plate showing another modification.

Figure 8 is a side elevation showing the two corresponding ends of the mop head.

Figure 9 is an enlarged detail sectional view taken approximately on the line 9—9 of Figure 6.

As shown on the drawings:

The reference numeral 10 indicates a frame or plate preferably of metal on which is removably held a mop head 12 composed of a plurality of strands of cord, yarn or other fibrous materials held together by a band or binding tape 14 at the top thereof. The plate 10 is approximately triangular in form, as shown, but is provided with rounded corners 16 and the sides thereof are made in the form of obtuse angles which have their apices 18 at about the middle point and the same extending outwardly, as best shown in Figures 1, 5, 6 and 7 of the drawings. This particular shape constitutes one of the most important features of the invention,

2

and was designed for the purpose of providing a better and closer fit between the sides of the frame and the mop head when drawn into position thereon. One side of the frame 5 10 is cut away in the form of a semi-circular arc-shaped recess, as shown at 20, to provide for the insertion of fastening or attaching means for the ends of the tape or band 14 of the mop head 12.

10 This fastening or attaching device preferably consists of a suitable bolt or bar 22 having threads on one end thereof for co-operation with a wing nut 24, as best shown in Figure 2. The other end of this bolt 22 15 is attached by means of spot welding, soldering, or the like, to a U-shaped plate 26, which extends upwardly through slots 28 in the plate 10 and is adapted for the pivotal attachment of the socket member 30 20 for the mop handle thereon. The socket member 30 is provided with threads 31 for the ready insertion of the mop handle and its lower end is formed in the shape of a U, as shown at 32 in Figure 4, which U fits 25 inside the U-shaped clamp 26 projecting upwardly through the slots 28 in the base 10 and is held in pivoted relation thereto by means of a bolt 34 having a nut 35 thereon, which bolt passes through a series of 30 aligned holes or openings in the U-shaped members 26 and 32 respectively. The sides of the U-shaped bolt or clamp are each punched out slightly above the plate 10, as is best shown at 36 in Figure 3, to provide 35 a tight fit between the U-shaped member 26 and the slits 28 in the plate 10 and to securely hold said member in upwardly extending position. If desired, the connecting U-shaped clamp 26 may be provided 40 with downwardly extending ears 40, as shown in Figure 3, having threaded openings therein adapted for co-operation with one end of the threaded bolt 42 having integral therewith on the other end thereof the winged nut-like head 44 for manipulation of same.

The plate 10 is provided on all of its three sides with downwardly extending inwardly curved flanges 50, as shown in Figures 3 and 5, which preferably are separated at the points 18 and at the rounded corners 16 and also at the recess 20. These 50 inwardly curved downwardly extending flanges 50 are provided for a close fit and gripping coaction with the tape or band 14 of the mop member 12, as best shown in Figure 2. A modification of this arrangement is shown in Figures 6 and 9 wherein additional holding members are provided in 55 the shape of punched out extensions 60 of the plate 10 which project in the same plane as the top of said plate and are adapted for the purpose of holding the mop head 14 more securely in position and especially to 60 prevent upward displacement thereof. In this modification the flanges 56 are shown as continuous around the sides of the plate 10, which form of course may be varied if desired, and these flanges are shaped in the form of a straight downward extension, as 70 shown in Figure 9, having an outwardly extending lower portion or edge thereof 57 parallel to the plate 10. If desired, the extension 57 instead of being made in a continuous straight line at the lower outer edge 75 thereof may be scalloped, as shown at 59 in Figure 7, which provides an additional gripping means for the mop binder 14.

The binder or tape 14 is provided with integral extensions 62, as shown in Figure 80 8, formed of the same material as the band but not enclosing or gripping any yarn or fibre 12. These extensions 62 are provided with metallic eyelets 64, as shown, for proper co-operation with the rod 22 or the 85 bolt 42 according to the particular construction of the head or frame upon which the mop body is to be attached. The length of the rod 22 or the bolt 42 is so adjusted that neither will extend beyond a line drawn 90 from one edge of the semi-circular recess 20 to the opposite edge so that there will be no possibility of either the bolt 22, winged nut 24 or bolt head 44 interfering with or scratching the furniture, floor or other objects upon which the mop is to be used. It will be seen that the bolt 42 having the head 44 thereon is of such a length that when the mop binder 14 is drawn down into 95 position upon the plate 10 and into close 100 conjunction with the flanges 50 or 56, the nut or head 44 will be well within the recess 20 so as to not interfere with the operation of the mop or scratch or mar the furniture or wall of the room.

105 The operation is as follows:

Whenever it is desired to place a new mop body upon the frame or plate 10 to replace one which has been worn out, the winged nut 24 or the bolt 44 is detached from the frame and the mop body fitted thereto and the eyelets 64 placed in proper position, after which the bolt or nut is tightened to 110 retain the mop in position on the frame, and it will be evident that the tension of the same can be adjusted by merely regulating the extent to which the tightening or holding bolt or nut is applied to the frame 10. The flange members 50 operate and coact 115 with the mop binder 14 to hold the same securely in position and any outward bulge due to the stiffness or bulkiness of the mop body and its consequent ill-fitting around the corners 16 of the triangular frame is compensated by the angles 18 in the sides, 120 as shown in Figure 1, thereby affording a very close fit and proper holding grip between all portions of the mop body and the sides of the frame 10. This is equally well 125 effected by the modification shown in Fig- 130

ures 6 and 7 wherein the mop binder or bead 14 is held securely in position by means of the ears or lugs 60 and the lower outwardly extending edges of the flanges 57 or 59. These members act to hold the mop body from either upward or downward displacement without any possibility of the same becoming loose or dropping off through use.

10 I am aware that many changes may be made and numerous details of construction varied throughout a wide range without departing from the principles of this invention, and I therefore do not purpose limiting the patent granted hereon otherwise than necessitated by the prior art.

I claim as my invention:

1. A mop including in combination a plate comprising a holding frame adapted to receive a mop body, a removable mop body attached to said frame, an upwardly extending lug inserted through the frame for attaching a handle socket, and mop body attaching means secured to the bottom portion of said lug.

2. The combination with a mop body having a bead formed on its upper edge, said bead being provided with openings adjacent its ends, of a mop head comprising a body portion, flanges arranged on said body portion and extending around the periphery thereof, one side of said body portion being provided with a recess, said flanges being cut away adjacent said recess, said body portion being provided with a pair of spaced slots, a member secured to the underside of said mop head, said member being provided with a pair of arms extending through said slots, a socket for the reception of a handle secured 40 to said arms, and a threaded rod secured to said member on the underside of the mop head, said threaded rod projecting beyond the edge of the mop head adjacent said recess.

45 3. The combination with a mop body having a bead formed on its upper edge, said bead being provided with openings adjacent its ends, of a mop head comprising a body portion, flanges arranged on said body portion and extending around the periphery thereof, one side of said body portion being provided with a recess, said flanges being cut away adjacent said recess, the body portion of said mop head being provided with a pair 50 of spaced slots, a substantially U-shaped member secured to the underside of the body portion of the mop head, the arms of said

U-shaped member extending through said slots and projecting upwardly, said arms being provided with aligned openings, a handle 60 socket pivotally mounted between said arms, a fastening element secured to the base of said U-shaped member, said fastening element being threaded and projecting outwardly beyond the body portion adjacent 65 said recess, the end of said threaded member being adapted to pass through the openings in the bead of the mop, and lugs for retaining the mop in position.

4. A mop head formed of a single piece 70 of sheet metal, said mop head comprising a body portion and a flange for the reception of the bead of a mop, said flange being arranged at right angles to the body portion of the mop head, a second flange formed on the 75 lower edge of said first flange and arranged substantially parallel to the body portion of the mop head to prevent downward displacement of the mop, and a plurality of spaced ears formed on the upper edge of said first 80 named flange to prevent upward displacement of the mop.

5. A mop holder including in combination a slotted plate comprising a mop holding frame, a clamp inserted through the slots in 85 said plate, and punched out portions in the sides of said clamp adapted to hold same firmly in position in the slots.

6. A mop holder including in combination a slotted plate comprising a mop holding frame, a clamp inserted through the slots in 90 said plate, punched out portions in the sides of said clamp adapted to hold same firmly in position in the slots, and means attached to said clamp to adjustably hold a mop in position 95 on said mop holder.

7. A mop holder comprising a slotted plate in the form of a triangle with the sides in the form of obtuse angles and with rounded corners, downwardly bent concave 100 integral flanges on the sides of the plate, said plate having a recess in one side thereof, a clamp inserted through the slots in said plate adapted to hold a handle socket, and means secured to said clamp and extending 105 outwardly beneath said recess and adapted to tighten a mop around said flanges.

In testimony whereof I have hereunto subscribed my name in the presence of two subscribing witnesses.

WILLIAM SEVERN.
